NON-CAPSIZABLE RECREATION BOAT

Bernard K. Dobkowitz, San Francisco, Calif.

Application July 22, 1957, Serial No. 673,282

1 Claim. (Cl. 9—3)

The present invention relates to improvements in a non-capsizable recreation boat. It consists of the combinations, constructions and arrangement of parts, as hereinafter described and claimed.

An object of my invention is to provide a non-capsizable boat having a shallow draft, and which is considerably smaller than a conventional row boat, and that is made to support fully grown persons without tipping over or sinking, even though the occupants move to one section of the boat.

More specifically stated, I propose to provide a hull having a buoyant member mounted on the exterior of a hull so as to provide a protective fender around the latter, this member being positioned to float in water when the boat is placed in a body of water. Moreover, the member is positioned so that when one portion thereof is elevated above the water, due to tilting of the boat, the elevated portion will act as a counterweight tending to restore the boat to an even keel. At the same time, an opposite portion of the member, which is depressed into the water due to the tilting of the boat, is positioned so as to tend to raise that part of the boat on which the latter portion of the member is disposed.

Another object of this invention is to provide a non-capsizable recreation boat, which is simple in construction, durable and efficient for the purpose intended, and which may be manufactured at a relatively low cost.

Other objects and advantages will appear as the specification continues, and the novel features will be set forth in the claim hereunto annexed.

Drawings

For a better understanding of the invention, reference should be had to the accompanying drawing, forming part of this specification in which:

Figure 1 is a top plan view of my non-capsizable recreation boat;

Figure 2 is a side elevational view thereof;

Figure 3 is a transverse sectional view taken along the line III—III of Figure 1; and

Figure 4 is a view similar to Figure 3, but showing the boat as being tilted due to shifting of the load to one side thereof.

While I have shown only the preferred form of my invention, it should be understood that various changes, or modifications, may be made within the scope of the appended claim without departing from the spirit thereof.

Detailed description

In carrying my invention into practice, I provide a hull indicated generally at A and defining a bow 10, opposite lateral sides 11 and 11a, a stern 12 and a bottom wall 13. The hull may be made of plywood or plastic, if desired, and a reinforcing trim strip 14 may surround the top of the hull. As shown, the bottom wall 13 is made flat so that the boat will have a shallow draft. Of course, I do not wish to be limited to any particular dimensions, but for the reasons hereinafter stated, the boat may be made

2

considerably smaller than an ordinary row boat. For example, I have found that a boat 24" wide, 16" high, and 6' long, when a buoyant member B is added to the boat, will amply support one fully grown person, without tipping over or sinking.

It will be noted that the buoyant member B is butted directly against and mounted on the exterior of the hull to extend horizontally and entirely around the latter. It is positioned adjacent to the bottom of the boat so as to float in water C when the boat is placed in a body of water on an even keel, as shown in Figures 2 and 3. This member serves as a protective fender for the hull when the boat strikes a wharf or other object. The member B may be made from 4" x 6" timbers (or their equivalent).

As suggested by the arrow 15, the load may shift to one side of the boat, and thus the port side 11 will be elevated above the water C, due to tilting of the boat. The elevated portion 16 of the member B will act as a counterweight tending to restore the boat to an even keel. The opposite portion 17 of this member will be depressed into the water at the starboard side of the boat due to the tilting, and it is positioned so as to tend to raise that part of the boat on which the latter portion of the member B is disposed. Obviously, when the load is shifted to the other side of the boat, the portion 16 will be depressed into the water, while the portion 17 will be elevated; with the result of tending to restore the boat to an even keel. The same will be true, if the boat pitches in the water so that its bow 10 or its stern 12 is elevated.

It will be apparent that the member B extends entirely around the hull A, including the bow 10, opposite lateral sides 11 and 11a, and the stern 12. As clearly shown in Figures 2, 3 and 4, the bottom wall 13 is flat and projects outwardly beyond the bow, opposite lateral sides and the stern. The member B rests directly on these outwardly projecting parts of the bottom wall for support thereby.

In Figure 1, I show a pair of adjustable seats 18, which are supported on cleats 19 so that these seats may be removed. Also, Figures 1 and 2 disclose a seat 20 for an infant, which is supported on cleats 21 so as to be removable. These seats may be disposed at any desired distance below the top of the hull.

It will be noted from Figures 2 and 3 that the opposite lateral sides 11—11a, the bow 10 and the stern 12 extend upwardly at substantially right angles to the flat bottom wall 13. The buoyant member B is rectangular in cross-section so as to fit into the angular junctions defined by the intersections of the outwardly projecting parts of the flat bottom wall with the bow, lateral sides and stern of the hull.

I claim:

- A non-capsizable recreation boat comprising:
- (a) a hull defined by a bow, opposite lateral sides, a stern, and a bottom wall,
- (b) the width of the hull being narrow in relation to its length,
- (c) elongated buoyant members of substantially square cross-section mounted on the lower exterior portions of the hull and extending entirely therearound so as to add to the displacement of the boat,
- (d) said buoyant members being positioned in abutting relationship with the bottom wall so as to float in water when the boat is placed in a body of water on an even keel,
- (e) said buoyant members serving as a protective fenders for the exterior of the hull,
- (f) said buoyant members being solid and having the density of timber, and being further positioned so that when one portion thereof is elevated above the water,

- due to tilting of the boat, this elevated portion by its own weight will serve as a counterweight tending to restore the boat to an even keel,
- (g) said buoyant members also being positioned so that when one portion thereof is depressed into the water such depressed portion will tend to raise that part of the boat to which it is attached due to its buoyancy,
- (h) the height of the hull being sufficient to prevent the boat from shipping water when a load in the boat is shifted to one side,
- (i) the bottom wall being flat so that the boat will have a shallow draft,
- (j) the said float bottom wall projecting outwardly be-

5 yond the bow, opposite lateral sides and the stern, to substantially the full extent of the buoyant members,

(k) said buoyant members resting directly on the upper surface of the outwardly projecting parts of the flat bottom wall for support thereby and said projecting parts of the flat-bottom serving as protection for the lower surfaces of said buoyant members.

Patent No. 2,932,040

April 12, 1960

Bernhard K. Dobkowitz

It is hereby certified that error appears in the above numbered patent requiring correction and that the said Letters Patent should read as corrected below.

In the grant, lines 1 and 12, and in the heading to the printed specification, line 3, name of inventor, for "Bernard K. Dobkowitz", each occurrence, read -- Bernhard K. Dobkowitz --.

Signed and sealed this 13th day of September 1960.
